UNITED STATES PATENT OFFICE

105,484

DESIGN FOR A COMMEMORATIVE EMBLEM OR SIMILAR ARTICLE

Robert Foster, New York, N. Y., assignor to New York World's Fair 1939, Incorporated, New York, N. Y., a corporation of New York

Application January 21, 1937, Serial No. 67,208

Term of patent 3½ years

To all whom it may concern:

Be it known that I, Robert Foster, a citizen of the United States, residing at 14 Sutton Place South, New York, county and State of New York, have invented a new, original, and ornamental Design for a Commemorative Emblem or Similar Article, of which the following is a specification, reference being had to the accompanying drawing, forming a part thereof, in which the figure is a face view of a commemorative emblem or similar article embodying my new design.

The article has no substantial thickness.

I claim:

The ornamental design for a commemorative emblem or similar article as shown and described.

ROBERT FOSTER.
